UNITED STATES PATENT OFFICE.

EDWARD G. SCHRIEFER, OF CINCINNATI, OHIO.

EXTENSIBLE CASE.

SPECIFICATION forming part of Letters Patent No. 739,725, dated September 22, 1903.

Application filed February 3, 1902. Serial No. 92,460. (No model.)

To all whom it may concern:

Be it known that I, EDWARD G. SCHRIEFER, a citizen of the United States, residing at Cincinnati, in the county of Hamilton and State of Ohio, have invented certain new and useful Improvements in Extensible Cases, of which the following is a specification.

My invention relates to extensible cases—such, for instance, as bookcases—and has for its object the providing of a case which may be built up section by section and in which the shelves may be suitably placed to desired positions without regard to the division-lines of the sections; and my invention consists in providing an extensible case adapted to be extended or built up section on section, so as to provide an unobstructed interior within the built-up case, in which shelves may be placed at desired points to form compartments either within a case-section or lapping over into a neighboring case-section; in providing a case-section constructed as a unit having a back and sides without top or bottom constructed and arranged for permitting a shelf to be passed up and down therethrough; further, in providing means in a case of the character described for preventing sidewise displacement or bulging of the sides of sections, and in providing a case of the character described with shelf-strips for supporting the shelves overlapping the division-lines of the sections of the case, and, further, in the parts and in the construction, arrangement, and combinations of parts hereinafter more fully described and claimed.

Reference is respectively made to my applications, Serial Nos. 92,461, 92,462, and 92,463, filed February 3, 1902, in which the case section or unit comprising a back and sides without top or bottom is shown, described, and claimed in other particulars.

In the drawings, Figure 1 is a perspective view of my improved device with its top removed. Fig. 2 is a perspective view of my improved device with the doors removed, showing the interior of the case and showing parts broken away for better illustration. Fig. 3 is a detail on the line $\alpha\alpha$ of Fig. 1. Fig. 4 is a front elevation of the shifting mechanism of the hanging device for the door with the front plate of its casing partly broken away and the door shown partly in section.

Fig. 5 is a plan view of the same similarly shown, showing also the connection between the hanging device and the side of the case 55 in section on the line $y\gamma$ of Fig. 6. Fig. 6 is a detail in side elevation, partly broken away and partly in section, illustrating the connection between the door-hanging device and side of the case. Fig. 7 is an end elevation showing the meeting ends between the doors. Fig. 8 is a detail, partly in section, showing the means for securing the shelf-strip to the case. Fig. 9 is a detail, partly in section, showing the means for securing the sections together sidewise; and Fig. 10 is a perspective view of a case-section and shelf therefor, also showing a shelf above and below the case-section in dotted lines to indicate that shelves may be passed through the 70 case-section while the top and bottom of the shelf are maintained in substantially horizontal planes.

A represents a section of a case. B is its bottom, and C its top. Each section has a 73 back 1 and sides 2, preferably close in construction for arresting dust. Each section is constructed as a unit and may be handled separately or placed in proper relation with other sections as an entirety. The top of the 80 sides of one section may have tongues 4, taking into grooves 5 at the bottom of the sides of the next section, or vice versa, to permit the sections to be slid upon one another and to strengthen the meeting points between the 85 sections or aiding in finding the proper relative position between sections in assembling a case. The back of the sections may have plane top or bottom edges or may also be provided with interlocking joints of suitable 90 construction.

Suitable sectional shelf-strips 11 12 are provided for each section, preferably of a length to correspond with the height of the section. They may extend below the section to which 95 they are secured, so as to take beyond the meeting edges of the sections into the section immediately below, as shown at 14. When the section has been put into place, the shelf-strips may be secured to the neighboring section in suitable manner.

When the shelf-strips overlap neighboring case-sections, they form means for holding the sides of the sections against sidewise dis-

placement or bulging, although it is obvious that other means may be employed for that purpose. The shelf-strips may be secured to the upper section before or after the sections have been put into place. I prefer to make this connection between the shelf-strips and the sections by means of a screw 15, taking through a washer 16 in the shelf-strip and into a thimble 17, secured to the case-section.

10 A composite case is formed by a bottom unit and a top unit, with a case section or sections placed in position between the same, the case when assembled having an unobstructed interior and permitting a shelf to be passed up and down therethrough while maintained in substantially its normal horizontal position, the case-sections being so constructed by having a back and sides without top or bottom that a shelf may be passed up and down therethrough with its top and bottom maintained in substantially horizontal planes, as indicated in Fig. 10, in which the shelf is shown in normal position at *a* and in positions *b* *c* above and below the case-section, such as it would assume in being passed through the case-section.

15 Immediately in front of the shelf-strips 12 I provide the sides of the sections with a longitudinal groove 21, adapted to receive a shoe 22 of the door-hanging device. The groove may have a U-shaped plate 25 therein, provided with a roughened or toothed backing 26, the shoe 22 having a corresponding contact-surface 27 for contacting therewith.

20 Each section is preferably provided with a door 31, which may be adapted to slide longitudinally of the case by having the shoe 22 slide in the plates 25 and to be positioned by having the shoe 22 make contact with the plates 25 for the purpose hereinafter explained. This engaging contact or release therefrom is effected by means of a shifting device for throwing the shoe into and out of engagement with the plates. In the form 25 shown I connect the shoe 22 with rods 32, turning in the shoe, so that the door may swing. The rods at one end may take through thimbles 33, longitudinal channels 34 being provided in the door for the rods. A rack 35 is at the inner end of each rod, the racks being meshed by gears 36 37, a pinion 38 meshing with the gear 36 and a gear 39 meshing with the pinion 38 and gear 37. The gears are hung in a casing 41, taking into a mortise 42 in the back of the door, the rods taking through openings 43 in the ends of the casing. The top of the casing forms a lug 44 for keeping the racks in mesh with the gears. The shaft 45 of the gear 39 extends forwardly 30 to receive a thumb-piece 46 for turning the gears in either direction, so as to force the shoes against the plates at the side or release their contact. The gear 39 has ratchet-teeth 47, engaging corresponding teeth 48 on a plate 49, hanging upon pins 50, to prevent its turning and to permit movement to and from the gear, the plate being forced toward

the gear by a spring or springs 51, thereby locking the rods in the position into which they may have been placed by the turning of the thumb-piece 46. The thumb-piece 46 may be countersunk into a recess 52. Catches 55 may be secured near the lower ends of the doors, the bolts 56 of which are adapted to snap into the grooves of the plates 25 for securing the door and may be forced inwardly by thumb-pieces 57 against the pressure of springs 58.

Shelf-rests 61 may be placed at desirable points along the length of the shelf-strips 11 30 12 for supporting shelves 62 without regard to the meeting points of the sections of the case to form a compartment either within a given case-section or extending beyond neighboring case-sections. In order that books or other articles in a compartment traversed by the hung end of the door may be readily accessible, I provide the means hereinbefore explained for raising and lowering the door 35 slidingly in the grooves. Stops 63 are provided in the grooves, against which the shoes 22 may strike when returning the door to proper position, so as to correctly position the door. I prefer to secure these stops in the lower ends of the grooves of a given section, so that the shoes of the door may be slid into their grooves from the top and so provide the least labor and greatest convenience for the user.

In my improved device the sections may 100 be superimposed to desirable height, and if it is desired to extend the case sidewise the tiers of sections may be secured together, as by means of bolts 65, taking through washers 66 and through an opening in one side 105 of one section and into thimbles 67 in the side of the neighboring section. When closed, the door preferably takes against the outer edges of the shelf-strips 12, the upper edge of the door being preferably rounded, as shown at 71, to provide for its swinging without obstruction, the outer part of the lower edge of the door next above being similarly rounded, as shown at 72, with a cushion 73 between the doors. The inner part of the lower 110 edge of the door is cut away, as shown at 74, to permit of the door being swung. The outer side of the door near its upper edge has a longitudinal recess 75 for accommodating the lower outer edge of the door next above. 115

I claim—

1. In an extensible case, the combination of a case-section constructed as a unit and comprising a back and sides and being open at top and bottom, with means attached to said sides for supporting and permitting adjustment of a shelf at various heights in said case-section, and a shelf arranged to be passed up and down entirely through said case-section.

2. In an extensible case, the combination of a case-section constructed as a unit and comprising a back and two sides and being open at top and bottom and having an interior constructed and arranged for permitting a

- shelf to be passed up and down therethrough while the top and bottom of the shelf are maintained in substantially horizontal planes, with means comprising strips of substantially the height of said sides secured to said sides for adjustably supporting a shelf at various heights in said case-section, and a shelf arranged to be passed up and down entirely through said case-section.
10. 3. In an extensible case, the combination of a case-section comprising a back and two sides and being open at top and bottom, a shelf therefor, means for adjustably supporting the shelf in the section, and constructed and arranged for permitting the shelf to be passed entirely through the section up and down while the top and bottom of the shelf are maintained in substantially horizontal planes.
20. 4. In an extensible case, the combination of case-sections constructed as units and comprising a back and sides and being open at top and bottom, shelves, means in the sections for supporting the shelves, a top unit, and a bottom unit, forming a case, all constructed and arranged for permitting a shelf to be passed throughout the inside of the case up and down while the top and the bottom of the shelf are maintained in substantially horizontal planes, and constructed and arranged for permitting case-sections to be placed and interchanged at various elevations in the case.
30. 5. In an extensible case, the combination of case-sections constructed as units and each comprising a back and sides and having open-ended top and bottom and arranged to be placed one on top of the other with upper and lower edges of respective sides meeting each other when so placed and forming a continuous interior throughout which a shelf may be passed up and down without obstruction, shelves, means arranged to be attached to each side of each case-section for adjustably supporting shelves at various heights throughout the combined interior formed by the case-sections, said case-sections arranged to be placed as an entirety interchangeably at various elevations for forming a case having the said continuous interior, and means for holding the sides of the case-sections against sidewise displacement irrespective of the height at which said several case-sections may be placed in said case.
40. 6. In an extensible case, the combination of case-sections constructed as units and comprising a back and sides and having open-ended top and bottom, a shelf, means in the sections for supporting the shelf, a top unit and a bottom unit, forming a case, all constructed and arranged for permitting a shelf to be passed throughout the inside of the case up and down while the top and bottom of the shelf are maintained in substantially horizontal planes, and means for holding the sides of the sections against sidewise displacement or bulging, said case-sections arranged to be

placed as an entirety at various elevations in said case.

7. In an extensible case, the combination of case-sections comprising a back and sides and being open at top and bottom, means for interlocking said case-sections, said sections being constructed and arranged for forming an extensible case with unobstructed interior by placing the case-sections so constructed as units one upon another and locking the same together at the sides, with a top and bottom unit, and shelves for the case, and means for adjustably positioning the shelves at any desirable height throughout the case, said case-sections arranged to be placed as an entirety at various elevations in said case, substantially as described.

8. In an extensible case, the combination of case-sections comprising a back and sides and having open top and bottom, with interlocking devices for the case-sections for forming a case with continuous unobstructed interior, shelves for the case, and means for adjustably securing the shelves to suitable position throughout the case, for forming unobstructed compartments within the case without regard to the meeting lines of sections, and a door for each section, swinging devices for the doors, with means for adjustably positioning the swinging devices with relation to the case-sections for dropping the doors longitudinally of the case upon their swinging devices and adjustably positioning the same for exposing any compartment without reference to the normal position of either shelves or doors, substantially as described.

9. In an extensible case, the combination of case-sections arranged to be placed one above another for forming a continuous unobstructed interior, with shelf-strip sections which overlap case-sections, with shelves arranged to be placed within the case at suitable points for forming compartments either within a particular case-section or overlapping case-sections, substantially as described.

10. In an extensible case, the combination, with a top and a bottom unit, of case-sections formed as units comprising a back and sides and having open-ended top and bottom arranged to be placed one upon another, with a locking device for firmly uniting the side of a section with the side of the section above the same at each side of the case for forming a case having a continuous unobstructed interior, a shelf and means arranged to be secured to said sides for adjustably securing the shelf at any desirable height for forming a continuous unobstructed compartment either within a case-section or overlapping case-sections, substantially as described.

11. In an extensible case, the combination, with a top and a bottom unit, of case-sections formed as units and comprising a back and sides and being open-ended at top and bottom, with locking device for firmly uniting superposed sides of superposed sections at

- each side of the case for forming a case having a continuous unobstructed interior, with shelves and means for securing the same for forming a continuous unobstructed compartment either within a case-section or overlapping superposed case-sections, and a door arranged to swing, with a hanging device therefor hung between and sliding longitudinally of the side of the case-section for exposing a compartment within a case-section when hung and swung in normal position and exposing a compartment overlapping superposed case-sections when hung in abnormal position, substantially as described.
15. 12. In an extensible case, the combination, with a top and a bottom unit, of case-sections comprising a back and sides and being open-ended at top and bottom, and interlocking devices between the case-sections for separately connecting together the sides of the case-sections at each side of the case when placed one upon another, said case-sections being constructed and arranged for forming an extensible case with continuous unobstructed interior, shelves for the case, means for adjustably positioning the shelves at any desirable height throughout the case for forming unobstructed compartments between adjacent shelves irrespective of the position of the shelves, said case-sections being constructed and arranged for being interchanged at various heights in the extensible case, substantially as described.
13. In an extensible case, the combination, with a top unit and a bottom unit, of case-sections constructed as units and comprising a back and sides but open-ended at top and bottom, constructed and arranged for forming an extensible case with continuous unobstructed interior, shelves for the case, means for adjustably positioning the shelves at any desirable height throughout the case for forming unobstructed compartments between adjacent shelves irrespective of the position of meeting joints between case-sections, with said case-sections constructed and arranged to be placed as an entirety interchangeably at various elevations in said extensible case.
14. In an extensible case, the combination of a door, with means for permitting the sliding of the door longitudinally of the case for arresting the sliding movement at desirable points lengthwise of the case, and means for swingingly supporting the door slidable with the door whereby it may be swung upon its supports in its arrested position, substantially as described.
15. In an extensible case, the combination of a door hung between and slidable longitudinally of the sides of the case, with shoes between the door and side of the case for forming the hanging contact for the door, means for forming and releasing the said contact at points at the limit and intermediate of the limit of the said slidable movement of the door, means for permitting the swinging of the door

upon its hanging contact device, and arranged for adjusting the door longitudinally of the sides of the case and permitting the swinging of the door in its adjusted position, substantially as described.

16. In an extensible case, the combination of independent superposed case-sections, of shelf-strip sections connected to one case-section and overlapping the next case-section and detachably secured thereto, said shelf-strip sections constituting continuations of each other throughout the case, independently-movable shelves in the case, and means for connecting said shelves to the shelf-strip sections at different points thereof, whereby the shelves can be held at various vertical elevations.

17. The combination with a case, of a door therefor swinging on a substantially horizontal axis, and means for securing the door at various desirable heights on said case.

18. In an extensible case, the combination of case-sections comprising a back and sides and being open at top and bottom, shelves for the case-sections, and means for adjustably securing the shelves to suitable position throughout the case-sections for forming compartments either within a case-section or overlapping case-sections and a door for a case-section swinging on a substantially horizontal axis, and means for securing the door at various heights on said case-section.

19. In an extensible case, the combination of case-sections, comprising a back and sides and being constructed with open top and bottom, means for connecting said case-sections for holding said sides against sidewise displacement, said sections being constructed and arranged for forming an extensible case with unobstructed interior by placing the case-sections so constructed as units one upon another and connecting the same at the sides of said sections, with a top and bottom unit, and shelves for the case, and means for adjustably positioning the shelves at various desirable heights throughout the case, with case-sections arranged for being interchanged in height in said extensible case.

20. In an extensible case, the combination of case-sections comprising a back and sides and having open top and bottom, means extending up and down between the sections at each side thereof for holding said sides against sidewise displacement, said sections being constructed and arranged for forming an extensible case with unobstructed interior by placing the case-sections so constructed as units one upon another and holding the sides of the case-sections against sidewise displacement, with a top and bottom unit, and shelves for the case, and means for adjustably positioning the shelves at any desirable height throughout the same.

21. In an extensible case, the combination of a case-section constructed as a unit and comprising a back and two sides and being open-ended at top and bottom, a door there-

for hinged between the vertical planes of extension of the side faces of a side of said case-section, with a shelf arranged to be passed up and down entirely through said case-section and means for supporting the shelf at various heights in said case-section.

22. In an extensible case, the combination of case-sections each comprising a back and sides but having open top and bottom for forming a continuous interior when said case-sections are placed one upon another, shelf-strips for the sides of each case-section of substantially the height of said case-section and arranged for forming substantially continuous shelf-strips when said case-sections are arranged one upon another, with shelves, and means engaging said shelf-strips for supporting said shelves.

23. In an extensible case, the combination with a top unit and a bottom unit, of case-sections constructed as units and each comprising a back and sides and being open at top and bottom and constructed and arranged to be placed one on top of the other for forming a combined case with the top and bottom units having an interior continuous throughout the case-sections throughout which a shelf may be passed up and down, shelves, adjustable shelf-supporting means in each case-section comprising strips of substantially the height of said case-section, the strips in the several case-sections forming substantially continuous strips of substantially the combined height of said case-sections placed one above another, said case-sections with their strips arranged to be placed and interchanged at various heights.

24. In combination an extensible case comprising a top section, a base-section, and a series of case-sections, said case-sections each constructed as a unit and comprising a back and sides and being open at top and bottom,

forming an extensible case having a continuous interior, a shelf arranged to be passed up and down entirely through the case-section, 45 with means arranged to be secured to said sides for supporting the shelf at various heights in the case-section, said case-sections arranged to be placed as an entirety interchangeably at various elevations in the extensible case.

25. In combination an extensible case comprising a top section, a base-section, and a series of case-sections, said case-sections each constructed as a unit and comprising a back 55 and sides and being open at top and bottom, for forming an extensible case having a continuous interior, a shelf arranged to be passed up and down entirely through a case-section, with means arranged to be secured to said 60 sides for supporting the shelf at various heights in the case-section, said means forming substantially continuous shelf-supporting means throughout the various case-sections when the latter are superposed, said case-sections arranged to be selectively placed at various elevations in the extensible case.

26. In an extensible case, the combination of case-sections arranged one above another, constructed as units and comprising a back 70 and sides without top or bottom, with shelves for the sections, and means for positioning the shelves at various heights in the sections for forming unobstructed compartments between adjacent shelves within a case-section 75 or overlapping case-sections.

In witness whereof I have signed my name hereto in the presence of two subscribing witnesses.

EDWARD G. SCHRIEFER.
